UNITED STATES PATENT OFFICE.

AUGUSTUS M. FENNER, OF LINESVILLE, PENNSYLVANIA.

BUILDING-BLOCK.

SPECIFICATION forming part of Letters Patent No. 680,138, dated August 6, 1901.

Application filed April 3, 1901. Serial No. 54,162. (No model.)

To all whom it may concern:

Be it known that I, AUGUSTUS M. FENNER, a citizen of the United States, residing at Linesville, in the county of Crawford and State of Pennsylvania, have invented certain new and useful Improvements in Building-Blocks; and I do hereby declare the following to be a full, clear, and exact description of the invention, such as will enable others skilled in the art to 5 which it appertains to make and use the same.

This invention relates to masonry, and has special reference to an improvement in building-blocks, particularly of the hollow type which are employed in the construction of the 10 walls and other parts of a building.

To this end the invention primarily contemplates improved means for effecting a firm and compact joint at the meeting ends of adjacent building-blocks.

20 The principal objection which masons find to the use of hollow blocks for building purposes is that in laying walls with such blocks it is practicably impossible to make good mortar joints, inasmuch as the walls of the building-blocks themselves are comparatively thin, and when the ends of blocks in the same course are brought together the mortar will press laterally out of the narrow space between adjoining ends of the blocks and 25 into the blocks, as well as upon the exterior thereof, so that it is practically impossible to hold the mortar at and between the ends of the hollow blocks sufficiently to make a good joint. Also by reason of the difficulty of providing good mortar joints at the ends of hollow 30 building-blocks masons have found it difficult with the expedients ordinarily used to securely fasten door and window frames in the wall.

40 It is the purpose of the present invention to obviate the above objections by providing simple and thoroughly-practical means for effecting substantial and compact joints at the ends of hollow building-blocks.

45 With these and other objects in view, which will more readily appear as the nature of the invention is better understood, the same consists in the novel construction, combination, and arrangements of parts, hereinafter more 50 fully described, illustrated, and claimed.

The essential features of the invention are necessarily susceptible to considerable modi-

fication without departing from the spirit or scope thereof; but the preferred embodiments of the invention are shown in the accompanying drawings, in which—

55 Figure 1 is a perspective view of a pair of adjacent hollow building-blocks united by a mortar joint, such as provided for by the present invention and showing the external 60 appearance of the joint. Fig. 2 is an elevation showing a section of wall, with a joint-block positioned within an end of one hollow building-block, ready to receive thereover the 65 companion building-block to be united thereto. Fig. 3 is an enlarged sectional view of a completed mortar joint embodying the preferred form of the invention. Fig. 4 is a detail in perspective of one form of joint-block 70 equipped with centering means in the form of rigid projections. Fig. 5 is an elevation showing a section of wall in which a small space is to be closed up by a short building-block and two mortar joints, the view illustrating joint-blocks equipped with a modified 75 form of centering means brought into play after the short building-block is dropped into place. Fig. 6 is a detail in perspective of the form of joint-block shown in Fig. 5. Fig. 7 is a view in perspective, showing the 80 use of a joint-block applied to the side of a door or window frame for use in connection with the terminal building-block laid against such frame. Fig. 8 is a detail sectional view of the joint formed by the mortar and the 85 joint-block in the arrangement of parts shown in Fig. 7.

90 Like numerals of reference designate corresponding parts in the several figures of the drawings.

In carrying out the present invention it is the purpose to provide means for producing a substantial and compact mortar joint for the ends of hollow building-blocks irrespective of the sizes or shapes thereof and at the 95 same time to provide means whereby substantially the same joint may be produced under the varying conditions incident to building a wall with hollow building-blocks. It is therefore unimportant what particular 100 size or shape of building-blocks is utilized in connection with the invention; but for illustrative purposes there are shown in the drawings building-blocks of the hollow type

and of the ordinary oblong rectangular formation, said blocks being designated by the numeral 1. Ordinarily in laying a wall with these blocks the ends thereof are brought together with an interposed film of mortar, which, however, as already explained, is pressed into as well as exterior to the blocks, so that a firm or good mortar joint is quite impossible. To obviate this defect in the laying of the building-blocks, the present invention contemplates the employment of an interior joint-block 2.

The joint-block 2 may be constructed of any suitable material, preferably of wood on account of the inexpensive nature thereof and the lightness, which facilitates the rapid handling thereof while the mason is at work. It is important in carrying out the invention that the wooden or other suitable joint-blocks 2 be of a sufficient thickness, so as to span the joint between contiguous ends of adjacent building-blocks, and it is also essential to the proper formation of the joint that each joint-block 2 be of the same shape as the rectangular or other cross-sectional shape of the building-blocks. Also each joint-block is of a slightly smaller width than the internal width of the building-blocks with which the same is associated in order to leave an interior annular mortar-space entirely around the periphery of the joint-block between such periphery and the inner sides of the building-blocks.

In the preferred forms of the invention the joint-blocks, which are employed at the joints between adjacent ends of building-blocks, are provided with centering means, whereby the same may be centered quickly and with reasonable accuracy directly over the joints. Different centering means may necessarily be employed, and in the form of the invention shown in Figs. 2, 3, and 4 the centering means consist in providing the joint-block 2, upon the periphery thereof and midway or at an intermediate point between the side faces thereof, with rigid projections 3 in the form of studs or pins, projecting a sufficient distance beyond the edge of the joint-block, so as to abut against the end of the building-block in which the joint-block is first inserted. In this form of the invention it is preferable that the centering means or rigid stop projections be omitted from one side edge of the block, which may be termed the "plain" side edge 4, in order to facilitate the initial setting of the joint-block with reference to the building-block, which has previously been placed in position.

The manner of using the form of joint-block already described is as follows: After one of the hollow building-blocks 1 has been laid in position on a wall the joint-block 2 is inserted facewise in the open end thereof until arrested by the centering means or stop projections 3, which therefore serve to hold the joint-block partly within and partly projecting out of the previously-laid building-block.

In thus positioning the block 2 the plain side edge thereof is placed down on a small amount of mortar first put under the joint-block, and after the latter has been arranged as described mortar is placed on the peripheral edge of the joint-block, as well as against the end of the building-block in which it is partly inserted. Then another hollow building-block is placed on the wall and driven gently over the protruding side of the joint-block, thus producing a solid and compact T-shaped mortar joint enveloping the peripheral edge of the joint-block and interposed between the contiguous ends of the building-blocks. The manner of arranging the joint-block, as described, is plainly shown in Fig. 2, and the T-joint is plainly shown in Fig. 3.

Where a small space between two hollow building-blocks is to be closed up, for instance, by a short building-block B and two mortar joints, as shown in Fig. 5 of the drawings, the block B necessarily has to be dropped downward into the space. Under such conditions the joint-block 2 is provided with modified centering means—such, for instance, as flexible pull connections or cords 5, fastened to the periphery of the block in the same positions as the projections 3 previously referred to, but sufficiently long, so as to be easily handled for centering the blocks. The joint-blocks 2 in the modification being described are also provided with plain side edges 4, and in using these blocks, prior to dropping the short building-block B in position, the joint-blocks having the flexible centering means are placed on edge inside of the hollow blocks that are already in position on the wall with their plain side edges 4 downward. After thus placing the joint-blocks the short building-block B is dropped into position, and by then pulling on the flexible connections or cords 5 the joint-blocks are centered over the joints at the ends of the short building-block B. The next step is to fill the joints with mortar.

Where the building-blocks are laid against door or window frames F, such as are shown in Figs. 7 and 8 of the drawings, a joint-block 2^a is nailed or otherwise fastened directly to said frame, so that the open end of the terminal building-blocks next to the frame will fit directly over the said joint-block and produce a joint in all substantial respects the same as already described.

Other modifications of the invention will necessarily suggest themselves to those skilled in the art, and it will be understood that various changes in the form, proportion, and minor details of construction may be resorted to without departing from the spirit or sacrificing any of the advantages of the invention.

Having thus described the invention, what is claimed, and desired to be secured by Letters Patent, is—

1. The combination with a hollow building-block, of an interior joint-block adapted to span the joint at the end of the building-

block and uniformly of a less width than the internal width of the building-block to leave an intervening mortar-space surrounding the entire periphery of the joint-block and extending the full width of the latter.

5 2. The combination with hollow building-blocks, of a joint-block arranged wholly therewith and spanning the joint between their contiguous ends, said joint-block having center-
10 ing means upon the periphery thereof, and also being of a less width than the internal

width of the building-blocks to leave an intervening mortar-space entirely surrounding the periphery of the joint-block and extending the full width of the latter. ¹⁵

In testimony whereof I affix my signature in presence of two witnesses.

AUGUSTUS M. FENNER.
